UNITED STATES PATENT OFFICE.

AUGUST C. POSNER, OF NEW ORLEANS, LOUISIANA.

DUST-COLLECTOR.

1,159,267.

Specification of Letters Patent.

Patented Nov. 2, 1915.

Application filed September 13, 1911. Serial No. 649,142.

To all whom it may concern:

Be it known that I, AUGUST C. POSNER, a citizen of the United States, residing in the city of New Orleans, parish of Orleans, and 5 State of Louisiana, have invented a certain new and useful Improvement in Dust-Collectors, of which the following is the specification.

My invention relates to that class of dust 10 collectors, which is termed the cyclone type, and has for its object to provide a machine, which will produce a higher efficiency, and as a consequence a higher vacuum in the inlet pipe adjacent the collector. I have 15 discovered that by locating a smaller collector within the outer one and extending the tubular guard of the interior collector up through the center of the purified air exit of the exterior machine that the efficiency of the machine is greatly increased. 20 This is believed to be due to the fact that instead of the central portion of the air escape being occupied either by a dead air space or an active ingoing current of air it 25 is taken up by a positive outgoing current of air, the velocity of which differing from the velocity of the current of air escaping at the periphery of the tubular guard of the outer machine greatly assists in expelling 30 the air from the collector. It is well known to persons skilled in the art that in machines of this type only an annular space adjacent to the periphery of the purified air escape is utilized for the escape of the air, the central 35 portion not only failing to show an outgoing current, but under ordinary circumstances showing a decided ingoing current. My means of accomplishing this object may be more readily understood by having reference 40 to the accompanying drawings, which are hereunto annexed and are a part of this specification, in which:

Figure 1 is a side elevation, part of the outer casing being broken away showing the 45 interior construction in section. Fig. 2 is a top or plan view of the same. Fig. 3 is a fragmentary detail view showing the adjustable valve.

Similar reference numerals refer to similar parts throughout the entire description.

For the purpose of illustration I have shown a collector in which both the upper and lower chambers are conoidal, though it will be apparent to persons skilled in the art

that the upper separating chamber may be 55 cylindrical without departing from the spirit of my invention as claimed.

As shown in the drawings, the collector is formed with an upper separating chamber 1, which is provided with a spiral inlet 2, 60 a conical dust discharge 3 attached to the lower part of the upper separating chamber 1. The purified air escape, is provided with a short tubular guard 4 preferably of cylindrical form. Leading from the annular 65 space formed between the tubular guard and the wall of the separating chamber 1 I provide a small dust pipe 12. This pipe operates to carry off the fine nearly impalpable dust which travels upwardly along the wall 70 of the upper separating chamber and which would be otherwise carried out through the escape provided for the escape of the purified air.

Within the upper separating chamber 1 I 75 mount a similar separating chamber 5, the walls 6 of which coincide in their taper with the taper of the walls of the separating chamber 1. This separating chamber has secured to its lower portion a tapering dust 80 discharge 7, and is provided with a spiral inlet 8, which extends, as more clearly seen in Fig. 2, to a point adjacent the wall of the upper separating chamber 1. This spiral is a continuation of the one formed by the inlet 85 on the exterior separating chamber. This has been found to operate most satisfactorily when located at a point near the opening of the tangential inlet 2. The inlet 90 8 is provided with a hinged portion, better seen in the detail views, which may be moved, as indicated, by dotted lines, nearer or farther from the wall of the outer separating chamber 1.

An annular member 9 constructed of flat 95 metal encircles the walls of the inner separating chamber 5 and a disk 10 is located in its interior, there being an annular space between the edge of the disk and the walls of the inner conical dust discharge 7. The upper separating chamber 5 is provided with a tubular guard 11, which extends upwardly 100 through the central portion of the purified air escape 4. The result of this construction is that the entire central portion of the 105 purified air escape is taken up by the air escaping through the tubular guard 11, and a careful examination fails to disclose any

rarefaction at the central portion of said guard, nor is there any ingoing air current there present.

The operation is as follows: To the guard 4, is secured in any suitable manner a pipe (not shown) leading from a vacuum producing fan, by which the dust-laden air is drawn into the upper separating chamber where it is whirled around, the heavier particles of dust being thrown outwardly to the periphery of the separating chamber and passed down along the walls through the conical dust discharge 3. As the whirling air current in its travel reaches the point where the spiral inlet 8 opens into the air chamber, it passes through the said tangential inlet into the internal separating chamber 5 where a further separation takes place, the dust passing, while the purified air escapes through the tubular guard 11. It will be apparent that the spiral will have carried the material downwardly so that a considerable separation will have taken place before the air current reaches the inlet 8. By this form of construction no interference is caused to the gyrating movement of the air and the operation in the internal separating chamber serves to collect that fine dirt, which as a rule escapes from the ordinary dust collector of this type.

By inserting a vacuum tube in the tangential inlet 2 the exact amount of draft produced by my machine can be determined and be materially increased by adjusting the hinged portion 13 on the tangential inlet 8.

Having described my invention, what I

regard as new and desire to secure by Letters Patent is:

1. A dust collector comprising an outer chamber and an inner chamber, each chamber having a spiral passageway, each passageway having a mouth extending beyond the periphery of the chamber to which it is applied, the mouth of the inner passageway being in a position to receive a current of air from the outer passageway, and an annular flange secured to the inner chamber for supporting the air current above the central plane of the chamber and a separate purified air discharge outlet for each chamber. 40 45 50

2. A dust collector comprising an outer chamber and a chamber supported within the outer chamber, a spiral passage way for each chamber, the mouth of the passage way applied to the inner chamber being arranged in a position to receive air from the passage way of the outer chamber, each chamber having a dust discharge portion, the dust discharge portion of the outer chamber being separate from the dust discharge portion of the inner chamber, and means for supporting a current of air above the central plane of the inner chamber and a separate purified air discharge outlet for each chamber. 55 60 65

In witness whereof I have signed the foregoing specification.

AUGUST C. POSNER.
